**GASOLINE SERVICE STATION ISLAND CANOPY
WITH ANNULAR LIGHT FIXTURE****Eliot F. Noyes, New Canaan, Conn., assignor to
Mobil Oil Corporation****Filed July 15, 1970, Ser. No. 23,948****Term of patent 14 years****Int. Cl. D25—99; D26—03
U.S. Cl. D13—1**FIG. 1

FIG. 2

FIG. 3

FIG. 1 is a perspective view of a gasoline service station island in combination with an annular light fixture positioned about the canopy support column.

FIG. 2 is a bottom perspective view of an upwardly radiating annular light fixture as shown in FIG. 1 positioned beneath a canopy and spaced apart from its support column.

FIG. 3 is a top view of the upwardly radiating light ring as shown in FIG. 2 arranged about the vertical column.

FIGS. 2 and 3 are perspective views of half rings arranged to form the annular light assembly positioned about the canopy support column shown in FIG. 1.

FIG. 3 shows an opaque annular area adjacent the

inner periphery of the upper translucent surface of the light fixture.

I claim:

The ornamental design of a gasoline service station island canopy with annular light fixture, as shown and described.
